US00D754000S

(12) **United States Design Patent**
Wang

(10) **Patent No.:** **US D754,000 S**
(45) **Date of Patent:** **** Apr. 19, 2016**

(54) **PUMP DISPENSER HEAD**

(71) Applicant: **Derjin (Hong Kong) Holding Company Limited**, Central (HK)

(72) Inventor: **Ya-Tsan Wang**, HsinChu (TW)

(73) Assignee: **Derjin (Hong Kong) Holding Company Limited**, Central (HK)

(**) Term: **14 Years**

(21) Appl. No.: **29/500,471**

(22) Filed: **Aug. 26, 2014**

(51) LOC (10) Cl. **09-07**

(57) **CLAIM**

The ornamental design for a pump dispenser head, as shown and described.

DESCRIPTION

FIG. 1 is a perspective view of the pump dispenser head;
FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines are shown for the purpose of illustrating parts of the pump dispenser that form no part of the claimed design.

1 Claim, 4 Drawing Sheets
